Patented Apr. 6, 1920.

FIG. 1.

FIG. 2.

B. H. Kessler

Inventor

By *Georg Kimmel*
Attorney

UNITED STATES PATENT OFFICE.

BENJAMIN H. KESSLER, OF TAMPA, FLORIDA.

ENGINE VALVE ATTACHMENT.

1,336,237.

Specification of Letters Patent.

Patented Apr. 6, 1920.

Application filed April 18, 1918. Serial No. 229,420.

To all whom it may concern:

Be it known that I, BENJAMIN H. KESSLER, a citizen of the United States, residing at Tampa, in the county of Hillsborough and 5 State of Florida, have invented certain new and useful Improvements in Engine Valve Attachments, of which the following is a specification.

This invention relates to improvements in 10 valve attachments for internal combustion engines of the valve-in-head type and it is the principal object of the invention to provide an attachment for eliminating all lateral or side play of the rocker arms thereof, 15 thus insuring proper functioning of the same and the valve and also reducing noise to minimum during operation.

Other objects will be in part obvious and in part pointed out hereinafter.

20 In order that the invention and the manner of its application may be readily understood by those skilled in the art, I have in the accompanying illustrative drawings and in the detailed following description based 25 thereon set forth a preferred embodiment of the invention.

In the drawings:

Figure 1 is a fragmentary top plan showing the improved attachment applied to the 30 rocker arms of an engine of valve-in-head type, and

Fig. 2 is an elevation of one of the novel devices.

Having more particular reference to the 35 drawings, in connection with which like reference characters will refer to corresponding parts throughout the several views, E designates a fragment of an internal combustion engine of the valve-in-head type, the 40 same having bearing arms *b* arranged upon the heads of the various cylinders thereof between which rocker arms *a* are pivotally mounted; said rocker arms, as will be understood, being adapted for intermittent engagement with the stems of the valve controlling the intake and exhaust ports of the engine cylinders and having connection with suitably timed operating mechanism, not shown.

50 Engaged with the rocker arms *a* are my improved play removing devices, the same comprising hooked elements 1 and 2, the inner ends of which are looped upon themselves and engaged with the adjacent ends of

contractile coil springs 3. As clearly shown 55 in the Fig. 1, the hooked members 1 and 2 are engaged over the rocker arms *a* and in this way serve to prevent any lateral or side play or movement of the same, thus, insuring proper functioning of the rocker arms 60 and the valves engaged thereby and further, reducing noise to minimum during the operation thereof. It will, however, be readily understood that the improved devices in no way interfere with the vertical movement of 65 the various rocker arms *a* engaged thereby and as a consequence, the intermittent engagement of said rocker arms with the adjacent ends of the intake and exhaust valve stems can be effectually carried out. 70

I of course desire to have it understood that the improved devices or attachments may be made in different sizes and further, that the hooked members 1 and 2 employed in connection therewith may be varied in design to allow their attachment to rocker arms differing in sizes and shapes. Furthermore, springs varying in tension may be employed, such as conditions or preference may dictate. 75

As above indicated, I do not wish to be understood as confining the invention to the particular embodiment chosen for illustration herein, nor to the exact construction, arrangement and adaption of parts shown and described, but I reserve the right to make any changes and alterations that fairly fall within the spirit and scope of the invention. 80

I claim:

1. In combination with the rocker arms of 90 an internal combustion engine, means for yieldably interconnecting the same to prevent lateral or side movement thereof.

2. In combination with the rocker arms of 95 an internal combustion engine, of resilient means disposed transversely of the same and engaged therewith for preventing lateral or side movement of the same but permitting free vertical movement thereof.

3. In combination with the rocker arms of 100 an internal combustion engine, of hooked members engaged therewith, and contractile coil springs engaged with the adjacent ends of said hooked members.

In testimony whereof, I affix my signature 105 hereto.

BENJAMIN H. KESSLER.
